UNITED STATES PATENT OFFICE

170,922

GAMEBOARD

**Larry H. Hayman and Anthony M. Silveri,
West Covina, Calif.**

Application May 1, 1953, Serial No. 24,790

Term of patent 7 years

(Cl. D34—5)

To all whom it may concern:

Be it known that we, Larry H. Hayman and Anthony M. Silveri, citizens of the United States, residing at West Covina, in the county of Los Angeles and State of California, have invented a new, original, and ornamental Design for a Gameboard, of which the following is a specification, reference being had to the accompanying drawing, forming part thereof.

The single figure is a top plan view of a gameboard showing our new design.

The gameboard is of a conventional thickness.

We claim:

The ornamental design for a gameboard, as shown and described.

**LARRY H. HAYMAN.
ANTHONY M. SILVERI.**
